CARPET STRETCHER

Filed Aug. 4, 1941

INVENTOR:-
JUSTIN D. BARTLOW.
By *Martin C. Smith, Atty.*

UNITED STATES PATENT OFFICE

2,326,117

CARPET STRETCHER

Justin D. Bartlow, Long Beach, Calif., assignor to
Jesse C. Owens, Los Angeles, Calif.

Application August 4, 1941, Serial No. 405,339

7 Claims. (Cl. 254—62)

My invention relates to carpet stretchers of the particular type covered by U. S. Letters Patent No. 1,766,423 issued to me June 24, 1930, also U. S. Letters Patent No. 2,108,506 issued to Jesse C. Owens February 15, 1938, and the principal object of my present invention is, to generally improve upon and simplify the construction of the carpet stretchers covered by the aforesaid patents, as well as other similar carpet stretchers utilizing an extensible member formed of a plurality of telescoping rods or tubes and one end of which member carries a head from which depends a series of carpet engaging prongs.

Further objects of my invention are, to provide improved means for projecting the forward portion of the extensible member, which forward portion carries the pronged carpet engaging head so as to rapidly and effectively stretch the carpet, further, to construct the projecting means so that it will automatically lock itself against reverse movement at the termination of the operation that imparts forward movement to the prong carrying head, and further, to provide a carpet stretcher of strong and substantial structure and which will perform its functions with minimum power requirements.

A further object of my invention is, to provide simple, practical, and easily operated means for adjusting the positions of the carpet engaging prongs with respect to the head that is carried on the forward end of the extensible member and which adjustment is particularly advantageous inasmuch as it enables the prongs to be utilized to best advantage on carpets that vary in thickness.

With the foregoing and other objects in view, my invention consists in certain novel features of construction and arrangement of parts that will be hereinafter more fully described and claimed and illustrated in the accompanying drawing in which:

Fig. 1 is a top plan view of the carpet stretcher constructed in accordance with my invention.

Fig. 2 is a longitudinal sectional view taken on the line 2—2 of Fig. 1 with the head shown in side elevation.

Fig. 3 is a cross section taken on the line 3—3 of Fig. 1.

Fig. 4 is an enlarged cross section taken on the line 4—4 of Fig. 1.

Fig. 5 is a cross section taken on the line 5—5 of Fig. 4.

Fig. 6 is a cross section taken on the line 6—6 of Fig. 5.

In the construction illustrated the frame of the stretcher comprises a pair of channel bars 50, the rear ends of which are connected to each other and to the forward end of the larger one of two or more telescopic tubes 51 and which are practically identical in construction and operation with the telescopic tubes disclosed in the hereinbefore mentioned patents, particularly the tubes 10, 11, 12 and 13 in Patent No. 1,766,423. The forward ends of the channel bars 50 are connected by a cross bar 52.

Formed integral with and projecting upwardly from the intermediate portions of the channel bars 50 are short posts 53 and seated in the upper ends of said posts is a transverse pin or bolt 54 that provides a fulcrum for a handle 55. The opening in the forward end of handle 55 that receives the fulcrum pin 54 is in the form of a short longitudinally disposed slot 56 and that portion of the forward end of the handle immediately below the forward portion of the slot 56 is cut away to form a notch 57.

Secured to the under side of handle 55 a short distance rearwardly from its fulcrum is a depending arm 58 and journaled in the lower rear side of said arm is a roller 59 which, when handle 55 is swung downward into a position substantially parallel with the frame of the stretcher and the telescopic tubes thereof, rides downwardly on the curved front face of a short arm 60 that projects upwardly from the connected rear ends of the channel bars 50. At the lower end of the downward swinging movement of handle 55 the roller 59 passes into a shallow notch 61 that is formed in the lower portion of the curved face of arm 60, thus yieldingly retaining the handle in its lowermost position.

The head of this form of stretcher includes a substantially rectangular housing 62 open at its bottom and suitably secured within the upper central portion of said housing is a block 63. Formed in the upper portion of this block is a notch 64 and arranged for sliding movement therein are the connected forward ends of the channel bars 50.

A plate 65 is removably secured on top of the central portion of housing 62 and provides a cover for the notch 64, and seated in recesses that are formed in the upper and under surfaces of the forward end portions of the channel bars 50 are anti-friction members 66, preferably balls, which bear on the surface of the block 63 at the bottom of notch 64 and against the under side of plate 65, thus minimizing friction be-

tween the head and the forward portions of the channel bars 50 upon which said head slides.

A transverse pin 67 seated in the lower end of arm 58 in front of roller 59 pivotally connects the rear end of a link 68 to said arm, which link extends forwardly to a point beneath the notch 57 in the forward end of handle 55 and the forward end of this link is connected by a pivot pin 69 to the upper rear end of a shorter link 70, the lower forward end of which is pivotally connected by a pin 71 to the rear central portion of block 63.

Mounted on the ends of pivot pin 69 that connects the links 68 and 70 are small rollers 72. Arranged for longitudinal sliding adjustment between the intermediate portions of the channel bars 58 is a block 73 which is secured after adjustment by means of a set screw 74 that is screw seated in one of the channel bars and formed in the upper portion of this block 73 is a vertically disposed slot 73a for the accommodation of link 68.

The forward edges of the walls to the sides of this slot 73a are inclined upwardly and rearwardly as designated by 75 to provide inclined bearings for the rollers 72 during a portion of the operation of the stretcher. Formed on top of the block in the bottom of the slot 73a is a lug 76 that provides a bearing for the link 68 during a certain portion of the travel of said link.

Rigidly fixed in the end portions of block 63 are the forward ends of rods 77 that project rearwardly from the head alongside the channel bars 50 and the rear end portions of these rods extend through short vertically disposed slots 78 that are formed in lugs 79, the same projecting outwardly from the sides of channel bars 50 (see Fig. 3).

Seated in the upper portions of the lugs 79 with their lower ends bearing on top of the rods 77 are screws or bolts 80 which provide means for adjusting the vertical positions of the rods 77 in the slots 78 and thereby counteracting tendency of the head 62 and parts carried thereby to skew or tilt downward while under carpet stretching strains.

Rigidly secured in the lower portion of the housing 62 of the head is a horizontally disposed plate 81 of wood or metal or a combination thereof, said plate being secured to the top plate of the housing by vertically disposed screws or bolts 82 and also being secured to the rear wall of the housing by screws 83. Seated in this plate are the upper ends of a series of downwardly and forwardly projecting prongs 84 that are adapted to engage the carpet that is being stretched.

A gauge to regulate the distance that the prongs enter carpets of different thicknesses comprises a vertically disposed plate 85 that is mounted for sliding movement against the inner face of the front plate of housing 62 and projecting rearwardly from the lower edge of this plate 85 across the under side of fixed plate 81 are two or more narrow plates 86 that are positioned between certain of the prongs 84.

Secured to each narrow plate 86 are the lower ends of a pair of posts 87 which pass through apertures 88 that are formed in the fixed plate 81. Formed on the upper portions of these posts 87 are flanges or shoulders 89 and positioned against the under sides thereof are the upper ends of expansive springs 90, the lower ends of the latter resting upon shoulders 91 that are

formed in the lower portions of the openings 88 through fixed plate 81. The normal tendency of these springs is to elevate the gauge comprising plates 85 and 86 and to yieldingly resist their downward movement.

In order to move the gauge downward so as to define the distance that the lower portions of the prongs may enter carpets of different thicknesses, a pair of wedge blocks 92 are arranged for sliding movement against the top plate of housing 62, each block having a pair of wedge-shaped portions, the under faces of which are notched as designated by 93 for the accommodation of the upper ends of the posts 87.

To move the wedge blocks 92 transversely within the housing for the purpose of adjusting the positions of the posts 87 and the gauge plates 86, screws 94 are seated in the rear wall of housing 62 and the ends of the screws within the housing pass through slots 95 that are formed in ears 96 and which latter depend from the corresponding ends of the wedge blocks. Formed on the screws 94 on opposite sides of the ears 96 are flanges or shoulders 97 and thus as the screws 94 are rotated the wedge blocks are correspondingly moved transversely within the housing.

The carpet stretcher described is particularly designed for stretching relatively heavy carpets and when used the stretcher is positioned on top of the carpet with the block on the outer end of the telescoping rods bearing against the wall or base board on one side of the room and with the head of the stretcher positioned on the carpet adjacent the edge opposite the edge that has been tacked or secured to the floor.

When handle 55 is swung upwardly and forwardly, the action of the links 68 and 70 draws the head comprising the housing 62 and parts therein rearwardly upon the forward portions of the frame members 59, and while in such rearward position the prongs on the under side of the head are engaged in the carpet after which the handle is swung rearwardly and downwardly into the position shown in Fig. 2.

This action through the links 68 and 70 moves the prong carrying head a short distance forwardly on the forward ends of the frame members 59 and during the final downward swinging movement of the handle the roller 59 bears against the curved face of arm 60, which action through the links moves the head a short distance forwardly and which action is possible due to the pin and slot arrangement 54 and 56 between the handle and the axis thereof. When the handle has been moved to its limit of downward movement, roller 59 will engage in notch 51 and such provision together with the position of the pivots 67 and 71 below center with respect to the fulcrum 54 and pivot 69, will maintain the handle in its lowered position and with the head at its forward limit of movement.

When the handle is subsequently swung upward and forward to retract the head in order to impart a second stretch to the carpet, link 68 will fulcrum on the lug 65, and as the rear end of said link swings upward the forward end thereof that is connected to link 70 will swing downward so that the rollers 72 will engage against and ride up the inclined surfaces 75 on the walls of block 73, thus minimizing friction of the engaging parts while the stretcher is in action. Block 73 carrying the fulcrum lug 76 and the inclined surfaces 75 may be adjusted longitudinally of the frame of the stretcher and se-

cured in such adjusted position by tightening the set screw 74.

To adjust the vertical position of the gauge comprising the plates 85 and 86, the screws 94 are actuated so as to move the wedge blocks transversely of the housing 62 and if said blocks are moved forwardly from the positions they occupy in Fig. 12, the posts 87 will be moved downward against the resistance offered by the springs 98 and corresponding downward movement will be imparted to gauge plates 86 which determine the effective length of the carpet engaging prongs 84.

The wedge-shaped portions of the blocks 92 are provided on their under faces with a plurality of notches 93 in order that the gauge plates may be adjusted into different positions with respect to the bottom of the head and thus the length of the effective portions of the prongs may be adjusted for carpets of different thicknesses.

Thus it will be seen that I have provided a carpet stretcher that is relatively simple in construction, inexpensive of manufacture and very effective in performing the functions for which it is intended.

It will be understood that minor changes in the size, form and construction of the various parts of my improved carpet stretcher, may be made and substituted for those herein shown and described, without departing from the spirit of my invention, the scope of which is set forth in the appended claims.

I claim as my invention:

1. In a carpet stretcher, an extensible member, a frame on the forward portion of said extensible member, a housing on the forward end of said member, a prong carrying plate positioned within said housing, a handle fulcrumed on said frame, links pivotally connected to and arranged between said handle and said housing and a block adjustably arranged within said frame and providing a fulcrum for one of said links.

2. A carpet stretcher as set forth in claim 1,

with the upper forward portion of said block provided with inclined surfaces and anti-friction rollers carried by said links for engaging the inclined surfaces of said block during a portion of the carpet stretching action of said stretcher.

5 3. A carpet stretcher as set forth in claim 1, with a vertically arranged curved surface on the rear portion of said frame and a roller carried by said handle for bearing against said curved surface during the final portion of the movement of said handle toward said frame and extensible member.

10 4. A carpet stretcher as set forth in claim 1 and with adjustable means between said frame and said housing for counteracting the tendency of the latter to tilt downwardly during the carpet stretching function.

15 5. In a carpet stretcher, the combination with an extensible member, of a housing on the forward end of said member, a prong carrying member secured in the lower portion of said housing, a guard arranged for sliding movement within and below said housing and means arranged within the housing and operable from the exterior thereof for moving said guard downwardly to regulate the effective length of the prongs carried by said member.

20 6. In a carpet stretcher, the combination as set forth in claim 5 and with means for yieldingly resisting downward movement of said guard.

25 7. In a carpet stretcher, the combination with an extensible member, of a housing on the forward end of said member, a prong carrying member secured in the lower portion of said housing, a guard arranged for sliding movement within and below said housing and means mounted for operation within said housing and operable from the exterior thereof for moving said guard downwardly into different pre-determined horizontal planes with respect to the bottom of the housing for regulating the effective length of the prongs carried by said member.

JUSTIN D. BARTLOW.
